UNITED STATES PATENT OFFICE.

SEVERIN N. SORENSEN, OF ST. PAUL, MINNESOTA.

DOCKAGE SCREEN FOR THRASHING MACHINES.

Application filed April 25, 1925. Serial No. 25,797.

My invention relates to screen or sieve structures of the general character usually designated as "dockage screens", especially adapted for use in connection with thrashing machines but, nevertheless, capable of more general use. Generally stated, the invention consists of the novel devices and combinations of devices hereinafter described and defined in the claim. In a sense, the present invention is in the nature of an improvement on or modification of the screen or sieve structure disclosed and claimed in the application of Harry L. Johnson, entitled "Dockage screen for thrashing machines", Serial No. 13,714, filed of date March 7, 1925.

In the use of dockage screens, much difficulty has been experienced in keeping the fine particles from lodging in and clogging the sieves. I have found that this difficulty may be overcome in the most effectual way by providing cleaning devices or scrapers operative on the upper as well as the under surface of the screen. One feature of the invention is directed to the arrangement above broadly indicated and to simple and efficient means for rendering the upper and lower sieve-cleaning devices simultaneously operative.

Other features of the invention will be hereinafter disclosed and particularly pointed out in the claim.

The invention is illustrated in the accompanying drawings, wherein like characters indicate like parts throughout the several views.

Referring to the drawings:

Fig. 1 is a vertical longitudinal section taken through the vibratory sieve shoe and associated parts of a thrashing machine, the said sieve shoe being equipped with my improved dockage screen and cleaning devices;

Fig. 2 is a fragmentary perspective showing a gate board removed from the sieve shoe; and

Fig. 3 is a plan view of the vibratory sieve shoe, dockage screen and cooperating cleaning devices.

Of the parts of the thrashing machine, it is only desirable for the purposes of this case to particularly note the framework 4 of the machine casing, the vibratory sieve shoe 5 with inclined bottom deck 6, and the upper or scalping sieve 7 mounted in the shoe in the customary way. The lower end of the deck 6, as shown, delivers to an auger-equipped

transverse trough 9. The shoe 5 carries a lower inclined deck 10 that delivers to a transverse auger-equipped trough 11. The inclined deck 6, rearward of its lower or delivery end, has a transverse dockage discharge passage 12 that is adapted to be closed at certain times by a gate-acting board 13, which, when applied, may be held in working position by any suitable means, such as clips or turn-buttons 14 applied to the bottom of the deck 6.

The dockage screen proper comprises a rectangular frame 15 having an intermediate transverse bar 15^a. A fine mesh sieve, which may be of any suitable structure but is preferably a perforated zinc plate 16, is secured to the lower portion of the frame 15 and covers all of that portion thereof that is below the transverse bar 15^a. All of that portion of the frame 15 that is above said bar 15^a is covered by an imperforate inclined deck 17 of sheet zinc or the like. The lower cleaning device is preferably made up of parallel longitudinal metal bars 18 and transverse wooden slats 19. The bars 18 work through the transverse bar 15^a or keepers mounted thereon and through the upper transverse bar of the frame 15, and their rear ends are turned upward at 18^a. The upper ends of the slats 19 are beveled and closely engage the under surface of the screen 16.

The upper cleaning device, preferably and as shown, is made up of a coarse mesh wire fabric 20 having a marginal frame 21. This wire fabric cleaning device rests loosely on the upper surface of the screen 16 and the transverse upper bar of the frame 21 is connected to metal straps 22, the ends of which are perforated so that the upturned ends 18^a of the bars or rods 18 are passed therethrough. Thrust rods or bars 23, at their forwardly extended ends, are perforated and applied around the upturned ends 18^a of the bars 18 and the rear ends of said thrust bars are anchored to a relatively fixed part of the machine frame, being, as shown, directly secured to eye-bolts 24, which bolts 24 are applied to angle bars 25, which, in turn, are bolted to the rear portion of the machine frame 4. The sieve shoe 5 will or may be supported by longitudinal vibratory movements by the usual means employed in thrashing machines and, of course, when the shoe is vibrated, the screen 16 will be carried therewith, and the upper and lower

cleaning devices being anchored will be caused to scrape and clean both the under and upper surface of said screen, thereby insuring dislodgment of all particles that may have become caught or stuck in the meshes or perforations of the dockage screen.

The perforations or meshes of the dockage screen 16 will be too small to pass therethrough either good wheat or good oats, but 10 all smaller seeds or particles, usually designated as dockage and including, for example, French weed, pigeon grass, buckwheat, barley, cracked and shriveled wheat, will be passed through said dockage screen 15 and onto the inclined deck 6.

In the operation of the machine, good wheat and oats, usually designated as "succotash", will pass off from the lower end of the screen 16 and into the trough 9, while 20 the dockage dropped onto the inclined deck 6 will be discharged through the passage 12 and either onto the ground or into a suitable receptacle that may be provided to receive the same. The coarse materials, such 25 as chaff, straw and the like, delivered from the lower end of the scalping screen 7, will drop onto the deck 10 and be delivered to the trough 11.

Sometimes, in the operation of the thrashing machine, it may not be desirable to sep-

arate the dockage from the good grain, and in that event, the board 13 may be used to close the passage 12 so that the dockage will be discharged off from the lower end of the deck 6 and into the trough 9, where it will 35 be recombined with the good grain.

The frame 15 of the dockage screen may be secured to the inclined deck 6 of the vibratory shoe 5 by screws, bolts, or in any other suitable way, and need not be removed, 40 when the machine is to be used for the separation of the dockage from the good grain.

What I claim is:

The combination with a relatively fixed frame and a vibratory shoe of a thrashing 45 machine, of a dockage screen applied to said shoe, a lower cleaning device working against the under surface of said screen and having extended bars with upturned rear ends, an upper cleaning device working on the upper 50 surface of said screen and having extended bars anchored to the upturned ends of the bars of said lower cleaning device, and thrust rods applied to the upturned ends of said latter noted bars and anchored to said 55 frame, said bars and thrust rod constituting means for causing a relative movement of said cleaning devices in respect to said screen.

In testimony whereof I affix my signature.

SEVERIN N. SORENSEN.
